[57] **CLAIM**

The ornamental design for a supporting bracket for a retractable handle of a suitcase, as shown and described.

DESCRIPTION

FIG. 1 is a front-left-top perspective view of a supporting bracket for a retractable handle of a suitcase, showing my new design;

FIG. 2 is a front elevational view thereof;

FIG. 3 is a rear elevational view thereof;

FIG. 4 is a left side elevational view thereof, the right side elevational view being a mirror image thereof;

FIG. 5 is a top plan view thereof;

FIG. 6 is a bottom plan view thereof; and,

FIG. 7 is a perspective view thereof, wherein the broken line showing of the of the suit case is for illustrative purposes only and forms no part of the claimed design.

1 Claim, 4 Drawing Sheets
